UNITED STATES PATENT OFFICE

JOSEPH McCRINK, OF WEST ORANGE, NEW JERSEY

DEMOUNTABLE-RIM TOOL

Application filed March 5, 1928. Serial No. 259,029.

This invention relates to a tool for contracting and expanding demountable rims of motor vehicle wheels to facilitate in removing and applying a tire.

5 One object of the invention is to provide a tool of this character embodying novel and improved features of construction whereby the tool automatically locks after the rim has been contracted so as to hold the rim so 10 contracted.

Another object is to provide such a tool which is adapted for initially breaking the joint of the rim to throw the ends thereof out of alignment, and which may also be 15 used for drawing the ends of the rim into alignment after a tire has been applied.

Further objects are to provide a rim contracting and expanding tool including a small number of simple and inexpensive parts 20 which are at the same time strong and durable; to provide such a tool which is easy and safe to operate and which eliminates the possibility of slipping of the tool and injuring of the hands of the operator; to provide 25 such a tool having strong and simply constructed and operated rim engaging clamps or hooks, and to obtain other advantages and results as will be brought out by the following description.

30 Referring to the accompanying drawing, in which corresponding and like parts are designated throughout the several views by the same reference characters,

Figure 1 is a plan view of my rim contracting and expanding tool illustrated in 35 position on a rim for contracting the same.

Figure 2 is a similar view showing the rim contracted.

Figure 3 is an enlarged transverse vertical 40 sectional view taken on the line 3—3 of Figure 1.

Figure 4 is a view illustrating the manner of using my tool for breaking the joint of a demountable rim, and

45 Figure 5 is a view similar to Figure 4 showing the manner of using the tool for pulling the ends of the rim into alignment for locking it.

50 Specifically describing the illustrated embodiment of my invention, my tool com-

prises an operating lever 1 which is preferably formed of a single flat piece of metal and which has pivotally connected to one end thereof as at 2, a rim engaging clamp or hook 3. A link 5 is pivotally connected at 4 to the lever 1 intermediate the ends of both the lever and said link, and a second rim engaging clamp or hook 7 identical with the clamp 3 is pivotally connected at 6 to the free end of the link 5.

60 Each of the rim engaging clamps 3 is shown as including a substantially U-shaped hook portion 8 of a shape to fit over the flange A of a demountable rim B and having one arm 80 offset at an angle to a straight shank 65 portion 9 and integral therewith, the hook portion including another arm 81 substantially parallel to the arm 80. The straight shank portion 9 is connected to the respective lever or link 5. Each clamp also has 70 threaded in the arm 80 a set screw 10 which is arranged to clamp the flange A of the rim between itself and the arm 81 of the respective hook portion.

75 As shown in the drawing the arm 11 of the link 5 is shorter than the arm to which the clamp is connected and the extremity thereof is preferably rounded as at 12.

In using the tool the clamp 3 is first secured 80 to one flange A of the demountable rim by means of the set screw 10 and the end 12 of the arm 11 of the link 5 is brought into abutting relation to the flange A at the other end of the rim B as shown in Figure 4 of the drawing. Pressure is then exerted on the 85 lever 1 in the direction of the arrow which breaks the rim and throws the ends thereof out of alignment as indicated by dot and dash lines. The clamp 3 is then removed and attached to the other end of the 90 rim, after which the clamp 7 is secured to the end of the rim to which the clamp 3 had first been applied. Pressure is then exerted on the lever 1 in the direction of the arrow which 95 draws the ends of the rim together to contract the rim as shown in Figure 2 of the drawing.

The ends of the lever 1 and link 5 connected to the clamps 3 and 7 are slightly offset as at 13 and 14 respectively so that the swing- 100

ing ends of the lever and the link may clear the sides of the rim as shown in Figures 2 and 3. However, these offsets are such that the hook portions 8 of the clamps are in the 5 plane of swinging of the lever 1, so that the lever will engage the set screw 10 in the clamp 3 and limit swinging of the lever as shown in Figure 2. It will be noted, however, that the parts are of such dimensions and so related 10 that the pivots 6, 4, and 2 are brought into dead center relation or slightly beyond as shown by dot and dash lines in Figure 2 so that the tool is automatically locked and holds the rim contracted.

15 If desired the arm 11 of the link and the lever 1 may be formed with respective openings 15 and 16 arranged to register with each other when the lever and the link are in alignment to receive locking pin 17 for positively holding the tool in locked position, that is, to hold the lever and the link with the pivots 6, 4, and 2 in dead center relation. As shown in Figure 3 of the drawing if the 20 set screw 10 were omitted the lever 1 would still engage the clamp 3 when the tool is in rim contracting position so as to limit swinging thereof beyond the locked position. To expand the rim it is merely necessary to swing the lever 1 in the direction of the arrow in 25 Figure 2, which brings the ends of the rim into the position shown in Figure 5. The clamp 3 is then attached to the outermost end of the rim and the arm 11 brought into engagement with the flange at the other end of 30 the rim after which pressure is exerted on the lever 1 in the direction of the arrow, which draws the ends of the rim into alignment, as shown in Figure 5.

The ends of the rim may be thrown into or 40 out of alignment by means of the tool with the parts in the position shown in Figure 2 of the drawing, that is with the lever 1 and link 5 in alignment with each other and with the pin 17 inserted through the openings 45 15 and 16 to hold the lever and link in said aligned position. If the rim is closed, by applying the two rim engaging clips 3 and 7 to opposite ends of the rim and exerting upward or downward pushes or pulls on the end of the 50 lever 1, the ends of the rim may be thrown out of alignment, while if the ends of the rim are out of alignment, pushes or pulls on the ends of the lever 1 will throw the ends of the rim into alignment.

55 Of course, the ends of the rim may be thrown out of alignment and into alignment by means of a hammer or other device for exerting the necessary blows or pressure on the ends of the rim, but my tool including the arm 60 11 of the link 5 is especially useful for this purpose and eliminates the necessity for a hammer or the like.

Having thus described my invention, what I claim is:

65 A demountable rim tool comprising a lever,

a link pivotally connected to said lever intermediate the ends of the latter, and rim engaging clamps each including a straight shank portion and a substantially U-shaped hook portion having one arm offset at an 70 angle to said straight portion and integral therewith and the other arm disposed substantially parallel to the first-mentioned arm to fit over a flange of a demountable rim, said straight portions being pivotally connected 75 respectively to one end of said lever and the free end of said link, each on the like side of said link and lever and the link being on the opposite side of the lever from the hook to swing in planes parallel to said lever and said link respectively, said link and lever being offset in the same direction as said hook to clear the rim as they are moved and said hook portions projecting across the end of the lever into the plane of pivotal movement of said 80 lever and said link so that said hook portion of the clamp connected to said lever serves as a stop to limit movement of said lever in the direction to contract said rim, and a set screw threaded in the first-mentioned arm of 85 each of said hook portions to clamp said flange between said screw and the second-mentioned arm of the hook portion.

JOSEPH McCRINK.
